UNITED STATES PATENT OFFICE.

ADAM REED, OF YAKIMA, WASHINGTON.

COMBINED ARCH SUPPORT AND SHANK STIFFENER.

Application filed December 26, 1924. Serial No. 758,158.

To all whom it may concern:

Be it known that I, ADAM REED, a citizen of the United States, residing at Yakima, in the county of Yakima and State of Washington, have invented new and useful Improvements in Combined Arch Supports and Shank Stiffeners, of which the following is a specification.

My present invention pertains to arch and foot supports, and it contemplates the provision of a simple and inexpensive device for the purpose set forth through the medium of which the bones in the arch of the foot as well as the metatarsal head will be held in proper position and at the same time act as a stiffener for the shank of the shoe to which it is secured.

Other objects and advantageous characteristics will be fully understood from the following description and claim when read in connection with the drawings accompanying and forming part of this specification in which—

Figure 1 is a view of a shoe partly in side elevation and partly in section showing my novel improvement arranged therein.

Figure 2 is an inverted view of an inner sole with my novel improvements arranged therein.

Figure 3 is a top plan view of the shank stiffener or arch support.

Figure 4 is an inverted plan view of the wear-plate and strap thereof.

Figure 5 is a longitudinal sectional view of the plate.

Figure 6 is a sectional view of the plate taken in the plane indicated by line 6—6 of Figure 4 and looking in the direction of the arrows.

Similar numerals of reference designate corresponding parts in all the views of the drawings.

In Figure 1 the numeral 1 indicates a shoe as a whole that is provided with the outer sole 2 and an inner sole 3.

Adapted to be secured to the lower surface of the shank of the inner sole 3 is a shank stiffener 4 that is anchored at its forward end to the inner sole 3 by means of a female fastener 5 and the said stiffener 4 is provided at its rear end with a tongue 6 as illustrated.

Secured to a point slightly forward of the center of the heel of the inner sole 3 by means of a stud 10 is a plate 8 that is provided with the integral loop 7.

It will be manifest that the member 4 is retained on one end in flexible manner to the inner sole 3 by means of the plate 8. This is accomplished by passing the tongue 6 through the loop 7 of plate 8 and the construction is of such a character that longitudinal movement of the member 4 is not precluded and at the same time wear of the inner sole at the point at which the tongue 6 would ordinarily bear is overcome by the plate 8.

I button on the inner surface of the inner sole 3 the pad 11 that is provided with the male fastener 12 that takes into the female fastener 5 and hence it will be seen that fastener 5 serves a two-fold purpose of not only holding the forward end of member 4 in position but likewise the pad 11 at the desired point.

In assembling the device a lining is preferably placed over the inner sole and when properly arranged freedom of movement of the foot as well as support of the arch, stiffening of the shank and the raising of the metatarsal heads is accomplished.

The device is a foot support and at the same time a shank stiffener and when equipped with the device the shoe will lose none of its attraction in appearance and yet will be comfortable to the wearer.

The invention is extremely inexpensive to produce and has no elements that could possibly become inoperative after a short period of use.

Having described my invention, what I claim and desire to secure by Letters-Patent is:—

In a combined arch support and shank stiffener for shoes, the combination of a plate having a fastening aperture therein and secured to the heel portion of the inner sole; said plate having an integral buckle formed thereon that is raised above the body of the plate, a stiffener having an aperture in one end thereof and being slightly decreased in width with respect to its body portion at the opposite end thereof, whereby a shoulder is formed in the stiffener that is adapted to abut one end of the plate buckle, a fastener adapted to secure the stiffener to the inner sole of the shoe and a pad adapted to be removably secured on the last named fastener.

In testimony whereof I have hereunto set my hand.

ADAM REED.
